INVALID CHAIR

Anna Marie McCormick Gray, Portland, Oreg.

Application October 23, 1948, Serial No. 56,210

5 Claims. (Cl. 155—28)

1

This invention relates to invalid chairs and is particularly adapted to be used by invalids.

The primary object of the invention is to provide an invalid chair whose seat can be adjusted up and down by either the invalid or the attendant while the invalid is seated in the chair.

Another object of the invention is the provision of means associated with the chair permitting the patient to get out of the chair and onto a bed, or onto the chair from the bed without the assistance of an attendant.

Another object of the invention is the provision of means within the chair for converting the chair into a horizontal table upon which the patient can recline.

A still further object of the invention is the provision of sanitary or lavatory facilities within the chair.

And a still further object of the invention is the provision of mechanism within the chair so that the same can be folded into a small space for facilitating transportation, or storage of the chair.

These and other incidental objects will be apparent in the drawings, specification and claims.

In the carrying out of the first object of my invention the seat of the chair is adjustable up and down relative to its supporting base. This adjustment being made by either the patient or the attendant so that the level of the seat can be adjusted to the level of a bed, depending upon the height of the bed. Then means is provided for lowering the back of the chair on to the bed so that the patient or invalid can transfer from the chair on to the bed or vice versa over the horizontally positioned back.

By providing this adjustment of the back up and down relative to the seat of the chair, the patient or invalid can move himself from place to place with the seat of the chair in a lowered position, which is safer and more comfortable, but at the same time being able to adjust the seat to any bed level. The ability of the patient to get in and out of the bed is the primary object of my invention.

In the carrying out of the further objects of my invention, the ability to convert the chair into a table or platform similar to a stretcher or operating table provides a most desired condition in the handling of patients or invalids.

The ability to fold the chair assembly into a small space is another outstanding feature, making it possible for the invalid to be moved from place to place with the least amount of effort.

Referring to the drawings:

2

Figure 1 is a side view of my new and improved invalid chair.

Figure 2 is a fragmentary detail view illustrating one of the features employed in the conversion 5 of the chair into a table or platform.

Figure 3 is another enlarged detail view taken on line 3—3 of Figure 2, illustrating the means of locking the particular elements together.

Figure 3A is a detailed fragmentary partially 10 broken away view of the driving sprocket and the brake mechanism.

Figure 4 is a front elevation of the chair in raised position.

Figure 5 is a detailed enlarged fragmentary 15 sectional view taken on line 5—5 of Figure 4, illustrating the foot rest assembly.

Figure 6 is a side view of the chair in lowered or folded position.

Figure 7 is an inverted plan view of the seat 20 assembly, taken on line 7—7 of Figure 1, illustrating a portion of the raising and lowering mechanism, and the sanitary or lavatory facilities associated with the chair.

Figure 8 is an enlarged detail sectional view of 25 Figure 7, taken on line 8—8, looking in the direction indicated.

Referring more specifically to the drawings:

My new and improved invalid chair consists of a horizontal base 1, which is supported by a pair of driving wheels 2 on its one end, and by the 30 caster wheels 3 at its opposite end. The driving wheels 2 revolve on a cross shaft 4, which is securely fixed to the frame 1 by any suitable holding means not here shown in detail. A pair of oppositely disposed arms 5 are pivotally mounted to the shaft 4, as best illustrated in Figures 1 and 4 at their lower ends, having stub shafts 6 journaled in their upper ends and revolved by the removable cranks 7.

40 Fixedly keyed to the stub shafts 6 are driving sprockets 8 which drive the chains 9, which in turn are trained about the sprockets 10, which are fixedly secured to the wheels 2. Each of the wheels 2 have their own individual driving assembly, as above described, including the cranks 7, chains 9 and the associated sprockets.

I have provided a braking mechanism, referring to Figure 3A particularly, wherein a dog 10A is pivotally mounted at 10B to the arms 5. 45 A spring 10C is fixedly mounted at 10D to the arms 5 at its one end, and to the dog 10A intermediately at 10E at its opposite end. This spring maintains the dog in the position shown over the dead center at one side due to its position 50 relative to the pivot point 10B, or it will hold

the dog in the dotted position over the dead center at the other side by the same principle. The dog is moved by the operator to either of the positions by the knob 10F laterally thereon, operating through the arcuate slot 10G in the casing 5', referring to Figure 1. The tip 10H of the dog engages the links of the chain 9 locking the same from movement when the dog is in the position illustrated in Figure 3A.

I will now describe the method of mounting the seat of the chair to the base just described. The seat consists of a horizontal base or main framework 11, having a pair of brackets 12 fixedly secured thereto at its rear and adapted to be pivotally mounted to the upper ends of a pair of oppositely disposed forwardly inclined side bars 13 at 14. The forward lower ends of the said bars being slidably mounted within the horizontal slotted guides 15 near the front and forming part of the base 1 at 13' as by means of rollers or otherwise. A second pair of rearwardly inclined side bars 16 are pivotally mounted to the frame 1 near the rear at 17 at their rear lower ends, having their upper ends slidably mounted within the guide ways 18, which in turn are fixedly secured to the base 11 of the seat, referring particularly to Figure 1.

The bar assemblies 13-16 are pivotally connected together at 19 where they intersect by suitable rivets or bolts, maintaining the assembly in a relative position regarding one another. The upper ends of the pair of bars 16 not only work within the guideways 18, but are pivotally connected at 20 to the elongated sliding members 21, which operate in the guideways 22 formed on the base of the seat 11, referring particularly to Figures 7 and 8. These elongated sliding members have threaded shafts 23 and 24 threaded therein. These shafts are geared together by the bevel gears 25 and 26 working in connection with the cross shaft 27. The shafts 23, 24 and 27 are journaled within bearings 28 forming part of the seat frame.

The end of the shaft 23 extends beyond one of the bearings 28 and terminates in a squared portion 29, which is adapted to receive the crank 30, also the end of the cross shaft 27 extends beyond the seat terminating in a squared end 31 adapted to receive the crank 30. A choice of location of the crank is determined depending upon the patient using the chair. By revolving this crank in either direction the threaded members 23 and 24 are rotated moving the sliding members 21 within their guideways 22, together with the upper ends of the bars 16, either raising or lowering the seat depending upon the direction of rotation of the crank 30.

The threaded shafts 23 in the threaded sockets or bores of sliding members 21 provide a locking means for holding the sliding members 21 in any adjusted position. The position of the driving cranks 7 mounted on the arms 5 is determined by the elevation of the seat. These cranks and arms are positioned by the braces 32, which are pivotally mounted at 33 to the base 1. The locking bolts 34 pass through the arms 5 and embrace the slots 35 of the braces 32, the same being locked in any desired position by the hand nut 36, thereby supporting the arms 5 at the desired angle or elevation relative to the operator of the wheel chair.

In Figure 1, I have illustrated the arms in an intermediate position in order to more clearly illustrate the balance of the drawing. These arms would be raised to a greater height when

the chair would be in this position under operating conditions.

I will now describe the mounting of the back 37 of the chair to the seat 11. This back is pivotally mounted to the brackets 12 at 38, and is held in any desired position by the arms 39, which have one of their ends pivotally connected to the back at 40, and their opposite ends connected to the arms 41 at 42. The arms 41 are pivotally mounted to the seat 11 at 43, the lower ends of the arms 41 have a quadrant portion 44 forming part thereof.

This quadrant consists of openings or holes 45 which register with the ends 46 of the locking bolts 47, referring particularly to Figures 1, 4 and 7. The opposite ends of the locking bolts are pivotally mounted to the lever 48, which in turn is pivotally mounted to the bracket 49 at 50. The bracket 49 is formed integral with the seat 11, providing a rigid support for the lever 48.

Referring to Figure 4, when the lever is moved in the direction of the arrow it will withdraw the ends 46 out of registry with the holes 45 of the quadrant 44 permitting the back 37 to be moved in either direction to the desired location, at which time the lever 48 is released and the spring 51 will cause the ends 46 of the bolts 47 to register with one of the holes 45 in each quadrant. This locking set up just described is adapted to hold the back at any desired angle above the horizontal line, but on reaching the horizontal line, especially when the same is being converted into a platform or stretcher, an auxiliary support is provided in the form of an extension brace 52, which is drawn out to the dotted position as illustrated in Figures 1 and 7, supporting the weight of the back thereon. This brace consists of a U-shaped member 53 slid in and out of the guideways 54, which are fixedly secured to the underside of the seat assembly.

I will now describe the construction of the foot rest and platform assembly, which consists of a telescopic assembly 55, comprising a series of telescopic plates 56, 57 and 58. These plates may be of a solid form or they may be made in the form of a perforated material. These plates are turned down at 59 at right angles on either side and reversed again at 60 to form channels, each one of the plates sliding within the other and being locked in the desired position by the locking bolts 61 and hand nuts 62, said locking bolts working within the slots 63, best illustrated in Figures 2 and 3. The telescopic plate assembly is pivotally mounted to the front of the seat 11 at 64, and is supported in the horizontal dotted position as indicated in Figure 1 by the telescopic foot 65, which is pivotally mounted at 66 to the upper plate 56. The lower end 67 is adapted to rest on the upper edge of the base 1, the exact detail of which is not illustrated.

When the invalid chair is being used as a wheel chair the telescopic assembly assumes the position as indicated in Figure 1, resting against the bracket 68 maintaining the same in a vertical position, the lower end 69 working up and down within the base 1, as the seat 11 is raised or lowered. Located on either side of the edge 59 of the upper plate 56 are loops or guides 70 adapted to support the bars 71 as best illustrated in Figure 5.

The notches 72 formed in the bars 71 engage the lips 73 of the loops holding the same in any desired location. Pivotally mounted to the outer extremities of the bars are foot rests 74.

By moving the bars through the loops the foot rest 74 may be moved away or towards the chair, and by selecting the various loops the foot rest can be raised and lowered relative to the chair, thereby providing a simple adjustment of the foot resting units.

Referring to Figure 8, I will now describe the sanitary or lavatory facilities of my new and improved invalid chair. A circular opening 75 is formed in the seat assembly 11 having a removable insert 76 for covering the same. A removable pan 77 is secured by clips 78 to the underside of the seat assembly, best illustrated in Figures 7 and 8. In order to remove or replace the pan the same is grasped by the handle 79 and moved sidewise from under the clips 78.

I will now describe the operation of my new and improved invalid chair. Referring to Figure 6, the chair is shown in folded or lowered position. In order to raise the same to the position illustrated in Figure 1, the operator applies the crank 30 to either the shaft 23 or the shaft 27 of the raising and lowering mechanism, depending on the working conditions encountered. By revolving the same in the proper direction the threaded shafts 23 and 24 will be threaded into the sliding members 21 pulling the upper ends of the supporting bars 16 towards the upper ends of the bars 13, causing the seat to raise.

The lower ends of the bars 13 travel along the guideways 15. When the patient is seated upon the seat considerable adjustment can be given relative to the height of the seat, after the same has been raised from the position shown in Figure 6, and this adjustment may be made by the patient or invalid themselves, by revolving the crank 30 in either direction. When it is desired for the patient to get in or out of bed from the chair, the seat is raised to the same level as the bed, the lever 48 is operated releasing the quadrant 44 permitting the back 37 to rest on the bed, thereby allowing the patient to swing over on to the bed from the chair by way of the back, providing a bridge, or out of bed onto the chair in the same manner.

In the event it is desired to place the patient on a table or stretcher, the quadrant 44 is unlocked, the back is lowered to the dotted position as indicated in Figure 1, the extension brace 52 is extended to the dotted position as indicated in Figures 1 and 7, supporting the back in a horizontal position. The telescopic plate assembly 55 is then raised to the dotted position, the telescopic foot 65 lowered as indicated in Figure 1, having its lower end 67 resting on the base 1 holding the same as indicated more completely in the detail shown in Figure 2, providing a brace for the patient's legs and feet to rest.

When the chair has been raised to a level to be used as a wheel chair, the arms 5 are adjusted by loosening the hand nuts 36 permitting the arms to be raised or lowered on the braces 32 to the desired position for operating the cranks 7, at which time they are locked relative to the braces. There are other adjustments that can be made for operating conditions, but I have described the major ones in the carrying out of my invention.

Although certain specific embodiments of the invention have been shown and described, it is obvious that many modifications thereof are possible. The invention, therefore, is not to be restricted except in so far as is necessitated by the prior art and by the spirit of the appended claims.

What I claim is:

1. A wheel chair comprising a mobile base frame, a seat, means adjustably supporting said seat from said frame including centrally pivoted levers on each side thereof and respectively pivoted at one end to said frame and seat and at the other end to slide means carried by said seat and frame, a rod journaled longitudinally on each side of said seat and respectively threaded into said slide means, a shaft journaled transversely of said seat and geared to said rods, and crank means selectively cooperative with said shaft and one of said rods to rotate said rods to threadedly adjust said slide means and vary the elevation of said seat relative to said frame.
2. A wheel chair comprising a mobile base frame supporting a seat, a back pivoted to the rear of said seat and movable between a vertical position and a horizontal position substantially level with said seat, a brace slidably supported beneath said seat and extendable to support said back in horizontal position, arm members pivoted at one end to the sides of said back and at the other end to links which are pivoted to the front of said seat, quadrants fixed with the seat ends of said links and having a plurality of aligned apertures, bolts slidable transversely beneath said seat with their outer ends protruding beyond the opposite sides of said seat for selective insertion in one of the apertures of said quadrants, a manually operable lever pivoted to said seat and to the inner ends of said bolts for retracting said bolts to adjust said quadrants and back, and a spring biasing said manually operable lever to eject the ends of said bolts.
3. A chair comprising a base frame, a seat, means adjustably supporting said seat from said frame, including centrally pivoted intersecting levers on each side thereof and respectively pivoted at one end to said frame and seat and at the other end to slide means carried by said seat and frame, a rod journaled longitudinally on each side of said seat and respectively threaded into said slide means, a shaft journaled transversely of said seat and geared to said rods, and crank means selectively cooperative with said shaft and one of said rods to rotate said rods to threadedly adjust said slide means and vary the elevation of said seat relative to said frame.
4. A wheel chair comprising a mobile base frame, a seat, means adjustably supporting said seat from said frame including centrally pivoted cross bars on each side thereof and respectively fixedly pivoted, one at its lower end to said frame near the rear end thereof and the other at its upper end to said seat near the rear end thereof, and at the other opposite upper and lower ends thereof respectively to slide means carried by said seat and frame respectively, a rod journaled longitudinally beneath and near each side of said seat and respectively threaded into said slide means carried by the seat, a shaft journaled transversely of said seat and geared to said rods, and crank means selectively cooperative with said shaft and one of said rods for operation by the occupant of the chair to rotate said rods to threadedly adjust said slide means and vary the elevation of said seat relative to said frame.
5. A wheel chair comprising a mobile base frame supporting a seat, a back pivoted to the rear of said seat and movable between a vertical position and a horizontal position substantially level with said seat, a brace slidably supported beneath said seat and extendable rearwardly to

support said back in horizontal position, horizontal arm members pivoted at one end to the sides of said back, upright links pivoted to the sides of said seat near the front thereof, said arm members being pivoted at their other ends to the upper ends of said upright links, quadrants fixed with the lower ends of said links and having a plurality of arcuately arranged concentric apertures, bolts slidably transversely beneath said seat with their outer ends protruding beyond the opposite sides of said seat for selective insertion in one of the apertures of each of said quadrants, a manually operable lever pivoted beneath the bottom of said seat and on opposite sides of the pivot of the lever to the inner ends of said bolts for simultaneously retracting said bolts to adjust said quadrants and back, and a spring biasing said manually operable lever to simultaneously eject the ends of said bolts into an aperture of each quadrant to hold the back in 20 adjusted position.

ANNA MARIE McCORMICK GRAY.
